UNITED STATES PATENT OFFICE.

IRA HUNTER, OF CARLISLE, KENTUCKY, ASSIGNOR OF ONE-HALF TO HORACE N. RANKIN, OF CARLISLE, KENTUCKY.

HAND-STAMP.

1,259,868.

Specification of Letters Patent. Patented Mar. 19, 1918.

Application filed June 13, 1917. Serial No. 174,596.

To all whom it may concern:

Be it known that I, IRA HUNTER, a citizen of the United States, residing at Carlisle, in the county of Nicholas and State of Kentucky, have invented certain new and useful Improvements in Hand-Stamps; and I do declare the following to be a full, clear, and exact description of the invention, such as will enable others skilled in the art to 10 which it appertains to make and use the same.

My invention relates to hand stamps and more particularly to that class of stamps which are designed to be used on coupons, 15 tickets and the like having a number of detachable portions.

The principal object of this invention is to provide a hand stamp for use on this character of tickets and coupons by which 20 a date may be stamped upon all sections of the ticket or coupon simultaneously, thereby saving considerable time and labor.

A further object of my invention is to provide a hand stamp of this character 25 which is so constructed that it may be readily grasped in the hand of an operator and gripped therein to manipulate the stamp.

Another object of my invention is to provide a stamp of this character in which 30 means are provided to guide tickets or coupons below the stamping member in such a manner as to be most efficiently operated thereupon.

A still further object of my invention is 35 to provide a stamp of this character which is of novel construction and of a novel operation and which will be cheap to manufacture, easy to operate and most efficient in effect.

With these and other objects in view, 40 which will appear from the description, my invention resides in the novel combination, construction and arrangement of parts to be more fully hereinafter described and 45 claimed and taken in connection with the accompanying drawings which form a part of this application and in which:

Figure 1 is a side elevation of the device; 50 Fig. 2 is a central vertical longitudinal section thereof;

Fig. 3 is a top plan view;

Figs. 4 and 5 are transverse sections on the planes of the lines 4—4 and 5—5 of Fig. 1;

55 Fig. 6 is an end elevation;

Fig. 7 is a perspective view of the ticket guide.

Briefly described, my invention comprises substantially a U-shaped frame having an inking pad suitably disposed at the closed end of the U. A second member is held by suitable means in sliding engagement with the arms of the U and carries a series of changeable dating stamps. These two members are provided with suitably formed backs to be grasped by the hand of an operator and gripped therein to move the members toward one another and as a means for holding them normally apart, I provide a spring interposed between the two members. Slidably engaging guide arms are extended from each of the members and are so constructed relatively to one another as to provide stops to limit the movements of the handle members into and out of engagement. Interposed between the handle members and located suitably above the inking pad I provide a removable guide adapted to receive coupons, tickets and the like and dispose the same most efficiently under the 70 dating stamp carried by the opposite handle member.

Referring more particularly to the accompanying drawings in which like reference characters designate corresponding parts throughout the several views, my improved stamp comprises a pair of handle members 1 and 2 respectively which are formed with straight longitudinal side edges and curved backs as clearly illustrated in 85 the accompanying drawings, whereby they may be readily engaged by the hand of an operator and grasped therein for manipulation of the stamp in a manner to be herein-after described. One of the handle members which is designated as 2 is provided with a longitudinally disposed chamber 3, one longitudinal wall of which is open to receive therein a detachably positioned inking pad 4. Arms 5 are provided at opposite ends of the handle member 2 and extend laterally therefrom in parallel relation and are provided with downwardly extending slots 6 therein adjacent their upper ends as clearly illustrated in Figs. 2 and 5 for a 90 purpose to be hereinafter described.

Spaced slightly above the ink pad and secured between the extending arms 5 is a frame 7 having its central longitudinal portions cut away as at 8 to provide an open- 100 105 110

ing therethrough for a purpose to be described. Slidably positioned in the frame 7 is a guide member 9 which is formed with a top and bottom wall 10 and 11 respectively 5 shaped to conform to the configuration of the frame 7 in which it is received and provided with outwardly and divergently extending lips 12 projecting outwardly from the side of the frame adjacent the open side 10 of the ink pad receiving chamber, as clearly illustrated in the accompanying drawings. This construction provides a guide member in which coupons or tickets to be stamped may be inserted between the divergently extending lips 12 and will thereupon be guided into the body of the stamp so as to be efficiently disposed therein beneath the stamp carried on the other handle member as will be hereinafter described.

20 The handle member 1 when in assembled position is disposed in alignment with the member 2 and is provided at its ends with a pair of laterally parallel extending arms 13 which are adapted to be engaged in slidable 25 relation against the arms 5 and are extended inwardly toward the handle member 2. Extending longitudinally between the arms 13 and mounted therein is a shaft 14 having its ends 15 projecting slightly beyond the arms 30 13 for engagement in the slots 6 formed in the wall 5 of the handle member 2. This arrangement serves to provide a guiding connection between the arms 5 and 13, whereby lateral displacement of the handle members 35 is prevented and the lower edges of the slots 6 are so disposed as to provide an effectual stop for the projecting ends 15 of the shaft 14 which will limit the movement of the two handle members toward each other.

40 At spaced intervals on the shaft 14 are mounted a series of changeable dating stamps 16 of the ordinary type and suitably secured at their upper portions to the handle member 1 so that when the handle members 45 are gripped together in the hand of an operator, the dating stamps 16 will be forced against the coupon or ticket which is inserted in the guide member 9, whereby to effectually stamp the same.

50 As a means for normally holding the dating stamps 16 out of engagement with the inking pad and raised above the ticket carrying frame, I provide a pair of spring tongues 17 at each end of the stamp suitably 55 secured at one end to the handle member 2 and extending at their upper ends under the adjacent portions of the shaft 14 to provide a spring support therefor and which will normally tend to force the two handle members apart. As a means of forming a guide between the slidable arms of the two members, I provide stop members on each of the arms 5 which comprise strips of metal 18 secured on the outer faces of the arms 5 bent 60 inwardly toward one another at the upper 65

ends of the arms and extended inwardly over said ends and looped as clearly illustrated in Fig. 1 and bent downwardly upon themselves and extended beyond their lower end and curved outwardly to form the clip 70 members 19. These strips are suitably secured to the arms by means of bolts or rivets and form stops to limit the upward movement of the members. These stops are provided in their looped inwardly projecting 75 portions with guide apertures 20 adapted to receive therethrough lugs or fingers 21 formed on the adjacent ends of the handle member 1 to provide a means of guiding the two arms when they are slidably engaged 80 and to prevent lateral displacement of the handle members.

In the operation of my improved stamp, it is merely necessary to insert a ticket or coupon in the guide 9 and to grasp the handle members in the hand and squeeze them together against the action of the spring 17 whereby an impression will be made upon the tickets or coupons upon all sections of the same simultaneously. The dating 90 stamps are of the changeable type and any desired date may be set as required. The clips 19 formed on the arms 5 provide a means for holding therein a plurality of the cards or coupons to be stamped so that they 95 may be withdrawn and used as desired. The details of the operation of my invention are clear from the description and it will not be necessary here to elaborate upon the same. I desire it to be understood that I do not 100 wish to limit myself specifically to the details of construction as described herein, but that any construction may be used and that any changes may be made in the minor parts thereof as will fall within the scope of the 105 invention as claimed.

I claim:

1. A device of the character described comprising a pair of handle members, one of said members having a series of simultaneously operated dating stamps thereon, an inking pad carried by the other member, slidably engaged guide arms projecting from the ends of said members, a spring between said members to normally hold them apart, and a guide between said members to receive a plurality of articles for simultaneous stamping.

2. A device of the character described comprising a substantially U-shaped frame having an inking pad disposed at the closed end of the U, means to guide a second member in sliding engagement with said arms of the U, a bar extending transversely of the second member, a plurality of stamps carried by said bar, a spring to hold said members in spaced relation and stops at the ends of the U to hold said second member from disengagement from the first.

3. A device of the character described 130

comprising a substantially U-shaped frame having an inking pad disposed at the closed end of the U, means to guide a second member in sliding engagement with the arms of the U, a bar extending transversely of said second member, a plurality of stamps carried by said bar, a spring to hold said members in spaced relation, stops at the ends of the U to hold second member from disengagement from the first and a guide posi-

tioned between said members to receive the plurality of articles for simultaneously stamping.

In testimony whereof I have hereunto set 15 my hand in the presence of two subscribing witnesses.

IRA HUNTER.
